ARMAND ACHILLE DELEPLANQUE, OF PARIS, FRANCE.

PORTABLE CIRCULAR SAW FOR WORKING METALS.

1,108,093.

Specification of Letters Patent.

Patented Aug. 18, 1914.

Application filed June 30, 1914. Serial No. 243,218.

To all whom it may concern:

Be it known that I, ARMAND ACHILLE DELEPLANQUE, a citizen of the French Republic, and residing at 139 Avenue d'Allemagne, Paris, France, have invented certain new and useful Improvements in and Relating to Portable Circular Saws for Working Metals, of which the following is a complete specification.

10 The present invention relates to a portable circular saw for working metals, in which the saw is maintained in correct sawing position by displacement of its axis according to a circular motion around the 15 driving shaft, with a view to form a compact machine of comparatively small weight, thus facilitating its transportation.

In the drawing which shows as an example of carrying out the invention a form of 20 construction of the saw more particularly adapted to sawing rails is shown:

Figure 1 is a vertical sectional view of the improvement: Fig. 2 is a section on line 2—2 of Fig. 1: and Fig. 3 is a section 25 on line 3—3 of Fig. 2.

The circular saw *a* is secured by means of suitable nuts on the axis *b*, on which is mounted a toothed wheel *c* meshing with a pinion *d* fitted on a shaft *e*, which holds at 30 its end opposite to the saw *a*, a driving wheel *f*, which may be a sprocket wheel, a toothed wheel or else a worm wheel, so that the driving of the wheel may be hand, electrically or mechanically operated.

35 The shaft *e* is fitted on the axis of a box *g* held so as to turn without being longitudinally displaced in a casing *h*, and the axis *b* of the saw is supported in bearings disposed in the said box *g* so as to compel said 40 axis to follow the rotary motion of the box.

On one of the faces of box *g* is keyed a worm wheel *i* meshing with a worm *j*, the axis *k* of which is provided with a driving wheel *m* allowing of its hand operation. To insure the automatic driving of said axis *k*, a ratchet wheel *n* is secured to the axis *k*, and engaging the ratchet wheel is a pawl *o* pivoted to one end of the bell crank lever *p*, whose other end *q* extends into the path of 50 the finger *r* on the wheel *f* so that the ratchet wheel *n* will be moved one tooth when the lever is engaged by the finger. The bell crank lever *p* is spring pressed and its swinging movement is limited by a 55 stop *p'*.

To reduce the vibrations of the machine, and avoid jarring, there is arranged around the box *g* a brake strap *s*, extremities of which are provided with tighteners *t*, *u*, which are externally supported on casing *h*, 60 so that they may be easily operated. Casing *h* is fixedly connected with a support for the purpose of receiving the iron pieces to be sawed, set-screws *y* in suitable number being disposed in a projection *z* of the casing, to 65 insure conveniently holding the machine on the iron to be sawed.

The device is operated as follows: The rotation imparted to wheel *f* by hand or by electrical or other means, is transmitted by 70 a suitable transmission predetermined by the ratio of the toothed wheels *d*, *c*, to the circular saw *a*. If wheel *m* be operated, the worm *j* and worm wheel *i* will cause the rotation of the box *g*, which produces displacement of the axis *b* of the saw on the dotted curved line *w* of Fig. 2, so that axis *b* may occupy the extreme position *b*¹ and *b*², according to the progress of the sawing. The shaft *e* being pivoted in the axis of box 75 *g* may freely turn while allowing of the free revolution of the said box, while the disposition of axis *b* in the bearings arranged in box *g* insures free rotation of said axis during displacement of the box, by the 80 travel of the pinions *c*, *d*, one upon another, this not being prejudicial to their meshing. Moreover the brake *s* absorbs the vibrations which might be produced, and by holding the box prevents any jarring; thus increasing 85 the efficiency of the saw.

The dimensions of the different members as well as the diameter of the saw *a* itself, may vary according to the various effects they are to produce. The whole machine 90 may be fitted on a stand or a slide-block to insure its stability, for instance for the sawing of bars of short length, while for the sawing of rails said slide-block would be useless, the whole machine being supported 100 on the rail to be sawed by means of the screws *y*. The driving of the saw may be effected directly or by means of any suitable transmission with an electric motor directly mounted on the casing, and the lubricating 105 may be effected by means of any known device.

The invention refers to the cutting of iron, or steel of any dimension and of any shape or section. The saw could also be 110

replaced by a mill, and the ratios of transmission may vary, so as to allow the use of the machine for the milling of all articles.

I claim:

- 5 1. A circular saw for sawing metal, comprising a casing, a rotary hollow member mounted in the casing, a driving shaft centrally mounted in the hollow member and having one end projecting beyond the said member and provided with a driving wheel on said end, said shaft being provided with a gear wheel within the said member, a saw shaft eccentrically mounted in the hollow member and having the end carrying the saw projecting beyond the end of the hollow member opposite that from which the driving shaft projects, said shaft being provided with a gear wheel within said member and meshing with the gear wheel of the driving shaft, and means for operating the said hollow member.
- 10 2. A circular saw for sawing metal, comprising a support, a rotary member mounted in the support, a driving shaft centrally

25 mounted in the rotary member, a saw axis eccentrically mounted in the said member and geared with the driving shaft, a worm wheel carried by the rotary member, a worm meshing with the worm wheel and carrying 30 a ratchet, a bell crank lever carrying a pawl engaging the ratchet wheel, and means connected with the driving shaft, for operating the bell crank lever.

3. A circular saw for sawing metal, comprising a support, a rotary member mounted 35 in the support, a driving shaft centrally mounted in the rotary member, a saw axis eccentrically mounted in the said member and geared with the driving shaft, means 40 for operating the rotary member, and a strap brake passing around the rotary member.

In testimony whereof I have hereunto set my hand at Paris (France).

ARMAND ACHILLE DELEPLANQUE.
